HEAT SENSITIVE DEVICE

Bruce D. Marshall and Thomas J. McCormick,
Detroit, Mich.

Application June 12, 1935, Serial No. 26,212

5 Claims. (Cl. 200—142)

This invention relates to electric heating devices and more particularly to a heat sensitive fuse therefor.

An important object of this invention is to provide a fuse or circuit breaker which is sensitive to external heat and which when the critical temperature is attained immediately disintegrates into a form which will not interfere with the working of surrounding parts and which may be removed, if desired, by simply blowing the disintegrated matter away. The fuse consists of such a composition that when the surrounding temperature has attained a certain degree, the body of the fuse disintegrates into a light, powdery form. The resulting powder formation is non-conductive and will not short the circuit. The disintegrative particles are small and light, and upon installation of a new fuse, the remains of the old need only be blown away.

Another object of this invention is to provide an improved construction for supporting a fuse which readily permits the insertion of new fuses. In the embodiment illustrated, the fuse is rod-shaped in formation and bridges two supports, each of which are provided with fastening devices to releasably secure the ends of the fuse. The fuse supports are adaptable to any type of heating devices, and in the embodiment illustrated herein it will be noted that the fuse is supported in readily accessible position.

Various other objects and meritorious features of the invention will more fully appear from the following specification, appended claims, and accompanying drawing, wherein:

Figure 1 is a side view partly in cross section showing the internal structure of the iron.

Figure 2 is a top view of the rear section of the iron with the cover removed.

Figure 3 is a fragmentary plan view of the heating element and the terminals leading thereto, and

Figure 4 is a detail view showing the manner of supporting and securing the fuse.

The heat sensitive fuse conducts the electric current and when the critical temperature is attained immediately disintegrates into a non-conductive powdery form. This fuse is composed essentially of magnesium alloyed with one or more metals which will be described in more detail hereinafter. Magnesium forms the major metal in the alloy and constitutes substantially 90% or more of the fuse composition. It is preferred that the fuse of magnesium alloy disintegrate at temperatures exceeding 1000° F., but it is to be understood that the relative propor-

tions of the ingredients can be varied to regulate the point at which the fuse disintegrates.

In the preferred form of the invention, magnesium is alloyed with either one or more of the following metals; aluminum, manganese, cadmium and copper. In these alloys, magnesium constitutes from 91.8% to 98.5% of the whole composition. The other metals enter into combination with magnesium in varying proportions. Each of the metals mentioned above may form the balance of the composition, that is, from 1.5% to 8.2% of the whole fuse composition. One such alloy may consist of magnesium and manganese in which magnesium forms 91.8% to 98.5% while manganese provides the balance of the fuse.

Another form in which the fuse of magnesium alloy may be made is magnesium alloyed with aluminum and manganese. In this form magnesium likewise forms 90% or more of the whole composition while the balance is made up of aluminum and manganese.

A still further composition may consist of all the metals listed above. Magnesium would constitute substantially 90% or more while the balance would be made up of relatively small proportions of all these metals.

When a magnesium alloy of that composition forms a part of an electric circuit in thermal relation to a device which will heat to relatively high temperature, the alloy will instantly disintegrate into a light powdery form the moment the critical temperature is reached. In this manner, it forms an excellent fuse for such electrical heating appliances as irons and the like. The disintegrated particles are so light that any deposit that they form may be blown away while the fuse supporting structure is made ready for another fuse. There is no mess nor any disintegrated metal parts which are likely to clog the operating parts of surrounding mechanism. After disintegration, the powdery material is non-conductive and it cannot short the circuit.

The fuse is supported in novel position providing ready access for replacement of a new fuse. In the drawing, reference numeral 10 indicates the body of an electric heating iron. The iron is provided with an electric heating element or coil 12 according to the usual design. The weighted portion 14 is cut away adjacent its rear end at 16 to form an enclosure for the electric terminals and the fuse support. The iron illustrated herein is of the type known generally as a cordless electric iron, but the invention is adaptable to any type of iron. Terminals 18 and 19 protruding from the rear of the iron are adapted to

contact live terminals on an iron stand and connect a source of electrical power with the heating element 12. The terminals are insulated from the iron by sheets of insulative material 20, such 5 as mica.

One of the exposed ends 22 of the heating coil is connected directly to the inner end of the terminals 18 as shown in Fig. 2. The other exposed end 24 of the heating coil is connected to a supporting bracket 26 forming one of a pair of such brackets for supporting a fuse. This bracket is L-shaped with the base of the L secured to an extension 28 of the weighted member 14 and insulated therefrom sheets of mica 30. A second fuse supporting bracket 32 is secured directly to the inner end of the terminal 19. Each of these brackets is bent over and provided with a flat top as shown in Figure 4. An adjustable clamping element 34 is secured to the top of each 15 of these brackets. Each of these clamping devices is provided with short turned down edge portions 36 and a long depending edge portion 38. The short depending portion rests upon the top of the bracket while the longer depending edge overhangs the top of the bracket as clearly 20 shown in Figure 4. A slot 40 is provided in one of the longer turned over edge portions 38. Bridging these brackets is rod 42 of fusible material, such as the magnesium alloy previously 25 described. The ends of this rod are secured under the clamping elements 34. One end is inserted through the slot 40. Tightening of the screws 44 will securely grip the fuse in position. When a 30 fuse has been disintegrated by the heat, another 35 may be inserted by simply releasing the gripping action of the elements 34 and inserting a new rod thereunder. It is to be noted that the brackets support the rod in a readily accessible position.

40 The ends 22 and 24 of the coil are not connected through the intermediary of bus bars of different metal to the terminal as is the usual practice. Instead, they are connected directly to the terminals themselves. Not only is this a less 45 expensive procedure but it prevents an unfavorable chemical action between dissimilar metals particularly when they are exposed to high temperatures and an electric circuit is delivered

therethrough. This action affects the metal conductors and increases their resistance.

Various modifications will be apparent to those skilled in the art and for that reason I intend to limit myself only within the scope of the appended claims.

We claim:

1. A circuit breaker sensitive to external heat comprising a rod of magnesium alloy including substantially 90% or more magnesium and relatively small percentages of aluminum and manganese.

2. A heat sensitive electric fuse comprising a magnesium alloy including magnesium as the major ingredient and relatively small proportions of aluminum, manganese, cadmium and copper.

3. A heat sensitive electric circuit breaker adapted to disintegrate into a non-conductive powdery form at temperatures exceeding 1000° F. comprising an alloy of magnesium and manganese.

4. A fuse construction comprising a pair of conductive vertical supports each having a flat topped portion, each of said supports provided with a metal element removably engageable with the top portion thereof, said elements having a relative short turned down edge adapted to rest on said top portions and a relatively long turned down edge adapted to overhang the edge of said flat portions, one of said overhanging portions having a vertical slot, and a heat sensitive fusible metal rod bridging said supports and having one end extending through said slot to be releasably engaged between one support and its cooperating metal element and having its other end likewise engaged between the other support and its cooperating metal element.

5. An electric fuse sensitive to external heat and adapted when the critical temperature is reached to disintegrate into a light powdery non-conductive substance, said fuse composed of an alloy of magnesium of which magnesium comprises the major ingredient and the remainder of the composition comprises one or more of the following metals: aluminum, manganese, cadmium and copper.
